JOHN BERCHMANS WELCH, OF NEW ORLEANS, LOUISIANA.

DRY KILN.

Application filed March 6, 1926. Serial No. 92,810.

This invention relates to apparatus for drying lumber and other similar materials and has for its object the provision of an improved drying apparatus.

5 In the drying of lumber it is important to maintain the humidity and temperature of the atmosphere of the drying chamber within proper limits so as to prevent too rapid drying, and, from a practical standpoint, it is 10 convenient to pass the lumber through an elongated chamber in which it is subjected to the drying operation and from which it emerges in a condition of the desired dryness.

15 During its travel through this chamber, the lumber should preferably be subjected to an atmosphere which progressively decreases in humidity from the entrance or wet end to the exit or dry end of the kiln, while 20 the temperature of the atmosphere at the same time progressively increases from the entrance to the exit ends. When these conditions are appropriately maintained, the rate of drying of the lumber as it moves 25 through the kiln will be substantially uniform, and abnormally rapid drying toward the dry end, resulting in damage to the lumber, will be avoided.

In accordance with the present invention 30 the drying chamber, throughout its lower part, is provided with a heating device comprising a plurality of full length "passes", and a relatively short "pass", of heating pipes, each of these passes being connected in series. The relatively short pass of heating pipes is located in the exit or dry end of the 35 drying chamber which it is desired to maintain at a somewhat higher temperature than the entrance or green end. A suitable supply header extends crosswise of the chamber 40 at a point between the two ends but nearer the discharge end, and supplies live steam directly to the relatively short pass of heating pipes. This relatively short pass is located 45 above the full length passes and the steam travels through the passes in series, the condensed steam flowing downwardly 50 through the series of passes and escaping through a suitable drain header to which the bottom end of the last full length pass is connected, this header being located at the dry or exit end of the kiln.

Thus the live steam first enters the relatively short passes of heating pipes, and returns in an opposite direction through the

relatively long passes of heating pipes immediately beneath the short passes. The direction of the now considerably cooled steam is again reversed as it is made to flow down through the still lower long passes of heating pipes, to the discharge header at the dry end of the kiln.

It is thus seen that the steam will have given up a very substantial part of its heat at the dry end half of the kiln, because of its 65 initial double return flow, before it reaches the wet end half of the kiln. Moreover, the gradual cooling of the steam in this manner assures a gradual transition in the temperature of the kiln from a point of relatively 70 high heat at the extreme dry end to a point of relatively low heat at the extreme wet end of the kiln. Hence, as the lumber is made to progressively move from the wet to the dry end of the kiln, the humidity necessarily 75 decreases as the temperature increases. Under properly controlled conditions, this is the end to be desired in the successful drying of lumber.

This invention will be more clearly understood by the accompanying drawings, taken in conjunction with the following description, in which:

Fig. 1 is a longitudinal section through the drying apparatus;

Fig. 2 is a horizontal section taken at a plane just above the heating device;

Fig. 3 is a section taken on line 3—3 of Fig. 2 to illustrate a detail of this support for the heating pipes; and,

Fig. 4 is a similar detail section taken on line 4—4 of Fig. 2.

Referring now to the accompanying drawings, the kiln for lumber drying comprises an elongated chamber 5 of concrete, wood or other appropriate heat insulating material, having the usual openings 6 and 7, provided with doors for the introduction and delivery of the lumber to be dried. The lumber enters in the usual manner on appropriate 95 trucks which run upon the rails 8 extending throughout the length of the kiln. These rails are supported upon transversely extending steel beams 9 which are supported upon posts 10 embedded in a suitable foundation 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

wet end at the left toward the exit or dry end at the right gradually decreases so as to provide a slight grade in the track 8 to facilitate the movement of the trucks of lumber.

The heating device is supported below the beams 9 and comprises the relatively short pass 13 of heating pipes which extend from the supply header 14 to the exit end of the kiln. Supply header 14 is located intermediate the ends of the drying chamber, preferably near the center thereof, but may be placed an appropriate distance either side of the center to give the required amount of additional heat at the dry end of the chamber. At this point the pipes constituting pass 13 are connected by return bends 15 to the pipes which constitute the intermediate full length passes 16. The pipes of this pass extend from the exit end through the entire length of the kiln to the green end where they are connected by means of return bends 17 to the pipes of the last pass 18 which extend through the entire length 25 of the kiln to the dry end and terminate in a drain header 18'.

Steam under appropriate pressure is supplied to the header 14 through pipe 19 in which there is located a controlling valve 20 which may be operated either manually or automatically by means of temperature variations within the drying chamber. The condensed steam collecting in drain header 18' passes out through a discharge pipe 21 in which there is preferably placed an appropriate steam trap (not shown) for the purpose of preventing the wastage of steam. Live steam is also supplied through pipes 22 to transverse steam spray pipes 23 provided with jets for directing the steam spray preferably toward the dry end of the kiln to facilitate circulation.

In the operation of the kiln the lumber enters at the opening 6 passing in the direction of the arrow progressively through the kiln and emerging eventually through the opening 7 at the dry end, steam being supplied to the heating device through the supply header 14. The temperature within the kiln will therefore be raised to the desired amount. In the example shown there are three passes of heating pipes, the first semi or incomplete pass 13 being located in the dry end. There are therefore three transverse banks of heating pipes in the dry end and only two in the green end of the kiln. Hence more heat is supplied to the dry end than to the green end, resulting in an increased temperature.

Inasmuch as the live steam is supplied directly to the relatively short pass 13 first, the dry end of the kiln gets the full benefit of the initially hot steam. Even after all of the heating pipes down to the drain header 18' are completely filled with steam, there

will be a temperature gradient along the steam pipes from the supply header 14 to the drain header 18'. As the relatively short pass receives the steam first and is located above the remaining full length passes it will be the hottest. The section of full length pass 16 which is connected to the return bends 15 will be the next hottest and as this is also located in the dry end it will supply a relatively large amount of heat to the dry end.

The last section of full length pass 18, that is, the portion of these pipes adjacent the drain header 18' and extending as far back as the region of supply header 14 are the coolest and the steam supplied to the header 14 through valve 20 can be regulated to produce a wide variation in the temperature of this section without radically varying the ratio of the heat supplied to the dry end to that supplied to the green end. Even if this section of pipe is allowed to remain substantially cool, or in other words, heated merely by the condensed steam which drains from the heating pipe sections above, a greater amount of heat is supplied to the dry end than to the green end. Hence because of this arrangement of the heating device the temperature of the atmosphere within the kiln may be varied so as to subject the lumber to different drying conditions without greatly reducing the ratio of heat supplied between the dry and green ends.

In order to appropriately support the several banks of heating pipes, cross bars 24 are provided at an appropriate spacing throughout the length of the heating pipes to the posts 10. These cross bars are lashed at their centers to the posts 10 by means of bolts 25 as shown in detail in Fig. 4. On either side of the centrally located posts 10 the pipes 24 extend underneath the beams 9 from which they are suspended by means of chains 26 (see Fig. 3). Bolts 27 are passed through appropriate lengths of the two depending portions of chain 26 to support the heating pipes at the desired elevations. By the use of these clamping means the desired gradient from the supply header 14 to the drain header 18' can be readily and conveniently secured. The holes in posts 10 are drilled at the proper positions by means of a hand drill and this determines the height of the centers of cross bars 24. Then the chains 26 are thrown over the tops of the beams 9 and the bolts 21 are passed through the appropriate links to support the outer portions of the cross bars at the same height as the centers.

By constructing a lumber drying apparatus in accordance with the principles of this invention, it is seen that lumber, which is progressively made to pass through the kiln, can be appropriately dried in such manner that it is simultaneously subjected to de-

creasing humidity and increasing temperature.

I claim:

1. In a drying apparatus of the progressive type, means for simultaneously decreasing the humidity and increasing the temperature from the entrance to the exit and ends thereof, including one short pass at the dry end for the initial introduction of steam and two long passes extending substantially the full length of the kiln through which to pass the steam leaving said short pass.

2. In a drying apparatus of the progressive type, means for simultaneously decreasing the humidity and increasing the temperature from the entrance to the exit ends thereof including relatively short return steam pipes for the initial introduction of steam at the dry end connected to steam pipes leading to the wet end and returning to the dry end.

3. In a drying apparatus, an elongated chamber for the material to be dried having a heating device in the lower part thereof comprising a plurality of heating pipes extending longitudinally of the chamber, said pipes being arranged to have a plurality of passes extending the full length of the chamber and a relatively short pass located at one end of the kiln, said relatively short pass being above the other passes and being connected to the steam supply pipe so as to receive the steam before it traverses the other passes, and means for controlling the feed-

ing of the steam to the relatively short pass.

4. In a drying apparatus, an elongated drying chamber for the material to be dried having a heating device in the lower part thereof adapted to maintain a higher temperature in one end of the chamber than the other, said device comprising a supply header extending cross wise of the chamber between the center of the chamber and the warm end, a drain header extending cross wise of the chamber at the warm end and located below the supply header, a plurality of heating pipes leading from the supply header to the warm end of the chamber, thence to the opposite end of the chamber and thence to the drain header, and means for controlling the feeding of steam to the supply header.

5. In a drying apparatus, an elongated chamber through which the material to be dried is carried during the drying operation, a heating device in the lower part thereof comprising a plurality of pipes extending longitudinally of the chamber in a plurality of vertically spaced passes, the uppermost pass extending for a portion only of the length of the chamber adjacent the exit end, means for supplying steam to the uppermost pass at the end thereof which is remote from the exit end of the chamber, and means for regulating the supply of steam to the heating device.

In testimony whereof I affix my signature.
JOHN BERCHIMANS WELCH.
